(57) **CLAIM**

The ornamental design for a lamp, as shown and described.

DESCRIPTION

FIG. 1 is a top, front, left side perspective view of a lamp showing my new design;

FIG. 2 is a top, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is a top, rear, left side perspective view of the lamp, in unfolded position, in condition of use; and,

FIG. 10 is a top, rear, right side perspective view of the lamp, in further unfolded position, in condition of use.

The broken lines in the drawings illustrate portions of the lamp that form no part of the claimed design.
